UNITED STATES PATENT OFFICE.

LOUIS AARON LEBOWICH, OF BOSTON, MASSACHUSETTS.

DESIGN FOR A FILE, CONTAINER, OR BOOK-COVER.

45,672.

Specification for Design.

Patented Apr. 28, 1914.

Application filed October 20, 1913. Serial No. 796,345. Term of patent 7 years.

To all whom it may concern:

Be it known that I, LOUIS AARON LEBOWICH, a citizen of the United States, residing at Boston, in the county of Suffolk and State of Massachusetts, have invented a new, original, and ornamental Design for a File, Container, or Book-Cover, of which the following is a specification, reference being had to the accompanying drawing, forming part thereof.

Figure 1 is a side view of a file showing part of my new design. Fig. 2 is a back view

of the file shown in Fig. 1 showing the other part of my new design. Fig. 3 is an end view of the file.

I claim:—

The ornamental design for a file, container, or book-cover as shown.

In testimony whereof I have affixed my signature in the presence of two witnesses.

LOUIS AARON LEBOWICH.
